MARKING DEVICE

John P. Capezzuto, Cambridge, Mass., assignor to The Carter's Ink Company, Cambridge, Mass., a corporation of Massachusetts

Filed Nov. 6, 1967, Ser. No. 9,291

Term of patent 14 years

(Cl. D74—17)

FIG. 1

FIG. 2

FIG. 3

FIG. 4

FIG. 5

FIG. 1 is a view in perspective of a marking device, showing my new design;

FIG. 2 is a side elevational view with the cap shown in exploded relation of the showing made in FIG. 1;

FIG. 3 is a front elevational view of the showing made in FIG. 1;

FIG. 4 is a front elevational view with the cap removed of the showing made in FIG. 2;

FIG. 5 is a top plan view with the cap removed of the showing made in FIG. 2, the top plan view of the cap being the same as shown in FIG. 2.

I claim:

The ornamental design for a marking device, substantially as shown and described.
